United States Patent Office

Des. 196,974
Patented Nov. 26, 1963

196,974

DRAWING STAND

George R. Korbos, St. Paul, Minn., assignor to Lakeside Industries, Inc., Minneapolis, Minn., a corporation of Minnesota

Filed June 21, 1962, Ser. No. 70,637

Term of patent 3½ years

(Cl. D25—1)

FIG. 5

FIG. 6

FIGURE 1 is a top plan view of a drawing stand embodying my new design;

FIGURE 2 is a side elevational view thereof;

FIGURE 3 is a vertical sectional view taken as on line 3—3 in FIGURE 1;

FIGURE 4 is a front end elevational view;

FIGURE 5 is the rear elevational view thereof; and

FIGURE 6 is a right front perspective view thereof, the side not being shown being identical with the side shown.

I claim:

The ornamental design for a drawing stand, as shown and described.
